CONTROL VALVE DEVICE

Arthur J. Bent, Penn Township, Allegheny County, Pa., assignor to Westinghouse Air Brake Company, a corporation of Pennsylvania

Application June 15, 1948, Serial No. 33,044, which is a division of application Serial No. 762,771, July 22, 1947, now Patent No. 2,608,052, dated August 26, 1952. Divided and this application January 23, 1951, Serial No. 207,337

3 Claims. (Cl. 137—622)

1

This invention relates to control valve devices of the self-lapping type and more particularly to a control valve device for controlling operation of a free piston machine, the present application being a division of my copending application Serial No. 33,044, filed June 15, 1948, which in turn is a division of my copending application No. 762,771, filed July 22, 1947, and now issued as Patent 2,608,052.

In Patent 2,406,037, issued on August 20, 1946, to R. P. Ramsey there is disclosed a free piston machine which embodies two oppositely and coaxially arranged motor compressor units each embodying a piston assembly comprising a power piston, an air compressing piston and a direct bounce piston, the two assemblies being arranged with a common power or combustion chamber between the two power pistons into which fuel is adapted to be injected for combustion to drive the two assemblies apart. At the outer face of each air compressing piston is an air compressing chamber and said piston is operative by the respective power piston to compress air from said chamber. At the outer face of each direct bounce piston is a cushion space known as the direct bounce chamber adapted to be supplied with fluid under pressure which is compressed on the air compressing stroke of the piston assembly to provide energy for moving the assembly inward preceding another power, air compressing stroke. At the opposite or inner face of the air compressing piston is what is known as a reverse bounce chamber which is employed in connection with starting of the machine and in which the amount of air is adapted to be manually varied for regulating, in addition to the usual regulation resulting from variations in fuel supply, frequency of reciprocation of the machine.

The principal object of the invention is the provision of an improved operator's control valve device particularly adapted for regulating the amount of fluid under pressure in the reverse bounce chamber or chambers of a free piston machine, such as above described.

Other objects and advantages will become apparent from the following more detailed description of the invention.

In the accompanying drawing; Fig. 1 is a sectional, diagrammatic view of a control valve device embodying the invention; and Fig. 2 is a sectional view, at an enlarged scale, of a portion of the structure shown in Fig. 1.

Description

As shown in the drawing, the improved con-

10 trol valve device comprises a casing containing a flexible diaphragm 48 subject on one side to atmospheric pressure in a chamber 49 which is open to atmosphere through a passage 50. At the opposite side of diaphragm 48 is a control chamber 51 adapted to be connected through a passage 52 to the reverse bounce chambers of a free piston machine (not shown) through a pick-off valve device (not shown) which will provide in said chamber 51 from the fluctuating pressure in said reverse bounce chambers a substantially constant, proportional or mean of the pressure in said reverse bounce chambers.

15 A diaphragm follower 54 contained in chamber 51 and engaging one side of diaphragm 48 has a stud portion 55 extending from one side thereof centrally through said diaphragm and secured by screw-threaded engagement to a sleeve 56 disposed in chamber 49. The sleeve 56 is provided 20 at one end with an annular collar 57 engaging and urging a follower 58 against the opposite side of diaphragm 48 for securely clamping the central portion of said diaphragm between said follower and the follower 54.

25 A sleeve 59 projects from the opposite side of diaphragm follower 54 through a bore in a partition wall 60 separating chamber 51 from a chamber 61 and thence through another partition wall 62 separating chamber 61 from a chamber 63.

30 Chamber 63 is adapted to be connected through a passage 64 to the reverse bounce chamber of a free piston machine (not shown) whereby pressure in chamber 63 will fluctuate with the pressure in said reverse bounce chamber during operation of said machine. Sealing rings 66 provided in the partition walls 60 and 62 have sealing and sliding contact with the sleeve 59 for preventing leakage of fluid under pressure from chambers 51 and 63 to chamber 61 which latter 35 chamber is open to atmosphere through a passage 67. A delivery pressure, regulating spring 68 contained in chamber 49 acts on the diaphragm 48 for urging it in the direction of partition wall 60.

40 45 A post 69 secured at one end to the diaphragm follower 54 extends centrally through the sleeve 59 to a point in chamber 63 beyond the end of said sleeve, while secured to the opposite end of said post in said chamber is the closed end of a cylinder 70 the opposite open end of which is disposed adjacent and in coaxial relation with the open end of sleeve 59. Slidably mounted in cylinder 70 is a fluid pressure release valve 71 arranged to cooperate with the end of sleeve 59, 50 constituting a seat for said valve, to control com-

munication between chamber 63 and the interior of sleeve 59 which is open through one or more ports 72 in said sleeve to the atmospheric chamber 61. A spring 73 contained in a chamber 74 formed between valve 71 and the closed end of cylinder 70 acts on said valve urging it toward its seat. Chamber 74 is open through a small port 75 in the closed end of cylinder 70 to chamber 63. The valve 71 has a stem 76 slidably mounted on the post 69.

The post 69 has a through axial bore and slidably mounted in this bore is a plunger 77 having an axial bore 78 closed at opposite ends of the plunger. Near one end the plunger 77 has one or more radial ports 79 establishing a constantly open communication between bore 78 and one or more radial ports 80 provided in the post 69 and opening to chamber 74. Near the opposite end the plunger 77 has one or more ports 81 connecting said bore to a release pilot valve chamber 82, it being therefore noted that chamber 82 and the release valve chamber 74 are in constant communication. A pilot release valve 83 contained in chamber 82 is arranged to control communication between said chamber and the atmospheric chamber 49 by way of a plurality of ports 84 in a seat member 85, a chamber 86 and a plurality of ports 87 in an equalizing member 88. The pilot valve 83 has a stem 89 extending through a suitable guide bore in seat member 85 into chamber 86 wherein it engages one side of an apertured spring follower 90. One end of a precompressed spring 91 contained in chamber 86 engages the opposite side of follower 90, while the opposite end of said spring is supported on a nut 92 adjustably mounted in the equalizing member 88. This spring is provided for unseating the release pilot valve 83 and for concurrently shifting the plunger 77 axially in post 69. Movement of plunger 77 in the opposite direction is adapted to seat the pilot release valve 83.

The equalizing member 88 has one end connected to the sleeve 56 which is secured to the diaphragm 48 for movement therewith. A balancing piston 93 is formed on the opposite end of equalizing member 88 and carries a sealing ring 94 having sealing and sliding contact with the wall of a bore in the casing, said piston separating a pressure chamber 95 at one side from a non-pressure chamber 96 at the opposite side which latter chamber is open to the atmospheric chamber 49 as by way of a passage 97. Chamber 95 is in constant communication through a passage 98 and passage 64 with the chamber 63. The diameter of the balance piston 93 is the same as that of sleeve 59 in chamber 63, so as to provide surfaces of said piston and of the release valve 71, when seated, of equal areas subject opposingly to pressures of fluid in chambers 95 and 63, 74, whereby oscillation or fluctuations in pressure in passage 64, and thereby in said chambers will not influence positioning of said parts and of the interconnecting parts above described.

The end of chamber 63 opposite that through which extends the sleeve 59 is closed by a casing part 99 having a through bore and mounted in said bore in coaxial relation to said sleeve is a bushing 100. This bushing has at the end adjacent chamber 63 an annular stop collar 101 seating in a recess in the casing portion 99, while engaging the opposite and outer side of the casing part and having screw-threaded engagement with an extended part of said bushing is a securing nut 102 for holding the bushing in place. A

number of sealing rings 103 spaced from each other are carried by the bushing 100 and have sealing contact with the wall of the bore in which said bushing is disposed to prevent leakage of fluid under pressure between chamber 63 and various passages to be hereinafter mentioned.

Slidably mounted in the bushing 100 is a plunger 104 having at one end a stem 105 of smaller diameter extending through a bore in an inwardly extending collar 106 provided on the bushing 100 adjacent its outer end. A sealing ring 107 carried by collar 106 engages stem 105 for preventing leakage of fluid under pressure along said stem from a balancing chamber 108 formed between the outer end of plunger 104 and the adjacent surface of collar 106. The plunger 104 has an axial bore closed at the end adjacent the stem 105, while the opposite end is open to chamber 63, and disposed in this bore against a shoulder 109a is a supply valve seat member 109. The member 109 is provided with a sealing ring 110 engaging the wall of the bore for preventing leakage of fluid under pressure from a supply pressure or supply valve chamber 111 formed at the inner end of member 109 within said bore past said member to chamber 63. The seat member 109 is supported in place in plunger 104 by a ring 112 disposed in a recess in said plunger and engaged by the outer end of said seat member. A main supply valve 113 contained in the supply valve chamber 111 is provided for seating engagement with the adjacent end of seat member 109 for controlling flow of fluid under pressure from said chamber to chamber 63 by way of an axial bore 114 extending part way through said member and thence through a plurality of ports 115 provided around a central integral section 116 of said member. The supply valve 113 is provided with an axial bore and surrounding said bore and extending into chamber 111 is a valve seat arranged to be engaged by a supply pilot valve 117 contained in said chamber. The pilot valve 117 is engaged by a follower 118 subject to pressure of a spring 119 for seating said pilot valve and in turn the supply valve 113. A pin 120 having a fluted portion 121 disposed within bore 114 in the seat member 109 has a coextensive fluted portion 122 of smaller diameter extending through the axial bore in the supply valve 113 into engagement with the supply pilot valve 117, a shoulder 122 being formed at the junction of the larger and smaller fluted portions. This shoulder 122 is spaced from the supply valve 113 when the pilot valve 117 is seated thereon but is adapted to engage and unseat said supply valve subsequent to unseating said pilot valve. The pin 120 has a bearing part 123 extending in the opposite direction from the fluted portions thereof through and in sliding contact with the axial bore in the integral section 116 of the seat member 109 into chamber 63 for engagement with the adjacent end of plunger 77.

The supply valve chamber 111 is adapted to be constantly supplied with fluid at a desired pressure through a passage 125 connected to a cavity 127 surrounding the bushing 100 and thence through one or more ports 128 in said bushing, an annular chamber 129 formed between said bushing and plunger 104 and encircling the latter, and one or more radial ports 129a in said plunger opening to chamber 111.

The chamber 63 at one end of plunger 104 is open through a passage 130 to chamber 108 at the opposite end for constantly equalizing pres-

5   sures of fluid therein to minimize the force required to move said plunger in the direction of chamber 63 when the latter chamber is supplied with fluid under pressure, as will be later described. Secured by a ring 131 to the plunger stem 105 adjacent the outer end thereof is a spring seat 132 and interposed between said seat and the bushing collar 106 is a bias spring 133 acting constantly to urge the plunger 104 outwardly of the casing part 99.

At one side of the plunger stem 105 the casing part 99 has an integrally formed projecting arm 134 in which there is secured by a pin 135 a shaft 136 extending parallel to the axis of said stem, and mounted to turn on this shaft in a plane at right angles to the axis of said shaft and stem is an operator's control lever 137. The lever 137 is secured against movement axially of the shaft 136 by means not shown in the drawing.

The lever 137 is provided with a cam element 146 having a cam surface 150 engaging one side of a follower 151 the opposite side of which engages the plunger stem 105, said cam being adapted when the lever 137 is in the position in which it is shown in the drawing to permit spring 133 to urge plunger 104 into contact with the bushing collar 106, while upon movement of said lever from this position in a direction away from the reader, said cam will displace said plunger in the direction of chamber 63 a distance proportional to the extent of such movement.

Operation

With plunger 104 in contact with the bushing collar 106, spring 119 will be seating the supply pilot valve 117 and supply valve 113, the regulating spring 68 will position follower 54 in contact with the casing partition 60, and spring 91 acting on the release pilot valve 83 and holding stem 77 in contact with stem 120, in turn in contact with said supply pilot valve 117, will hold said release pilot valve unseated. With the release pilot valve 83 open, chamber 74 and thereby chamber 63, passage 64 and the balancing piston chamber 95 will be vented to atmosphere through port 75 in cylinder 70, port 80 in post 69, port 79 in plunger 77, thence through the axial bore 78 and port 81 in plunger 77, chamber 82, past said release pilot valve, through port 84, chamber 86, port 87, regulating spring chamber 49 and passage 50. Since chamber 51 is open to chamber 63 via the reverse bounce chambers in the free piston machine (not shown) said chamber 51 will at this time also be vented permitting contact between the diaphragm follower 54 and partition wall 60 as above mentioned. With chambers 63 and 74 both vented spring 73 will be seating the release valve 71.

If the lever 137 is now turned in a direction away from the reader, the cam 146 and follower 151 will be operated to displace, as a unit, the plunger 104, the seated supply valve 113, the seated supply pilot valve 117, the pin 120 and the plunger 77 against the release pilot valve 83 and move said release pilot valve against spring 91 until it becomes seated. When the release pilot valve 83 becomes seated as just described it will hold the plunger 77 and thereby the pin 120 against further movement whereupon continued movement of the plunger 104 in the direction of these parts will cause said pin to first unseat the supply pilot valve 117 and then the supply valve 113, whereupon fluid under pressure

from the supply valve chamber 111 will flow past said supply valves to chamber 63 and thence through passage 64 to the reverse bounce chambers in the free piston machine (not shown). Fluid from chamber 63 will also flow by way of passages 64 and 98 to the balancing piston chamber 95 to act on the piston 93 to counterbalance the same pressure acting in chamber 63 on the cylinder 70.

When fluid under pressure is thus supplied to chamber 63 and the reverse bounce chambers of the free piston machine the pressure of such fluid will fluctuate with operation of said machine, but a substantially constant proportional or mean of such pressure will become effective through passage 52 in chamber 51 which will deflect the diaphragm 48 against the regulating spring 68 in accordance with the increase in such pressure, and relative to plunger 104 assuming that movement of lever 137 and of said plunger has been limited to some chosen degree. As the diaphragm 48 thus deflects under pressure of fluid becoming effective in chamber 51, the seated release pilot valve 83, plunger 77, pin 120, supply valve 113 and supply pilot valve 117 will, under the action of spring 119, move therewith relative to plunger 104 until both of said supply valves become seated to terminate supply of fluid under pressure to chamber 63 and thereby the increase in pressure of fluid in chamber 51, whereupon deflection of diaphragm 48 against spring 68 will cease, it being noted that the quantity of fluid under pressure obtained in chamber 63 and the pressure of fluid obtained in chamber 51 is limited according to the position of lever 137.

If the lever 137 is moved further away from the operator the plunger 104 will be displaced further in the direction of diaphragm 48 and, as a result, fluid under pressure will again be supplied to chamber 63 until a proportional increase is obtained in chamber 51 whereupon deflection of diaphragm 48 will permit closing of the pilot supply valve 117 and supply valve 113 to prevent further supply.

On the other hand, if lever 137 is pulled toward the operator the cam 146 will be so adjusted as to permit spring 133 to actuate the plunger 104 in the direction of said cam. The seated supply valve 113 and seated supply pilot valve 117 will move with the plunger 104 and thus permit spring 91 acting on the release pilot valve 83 to move said pilot valve and the plunger 77 along with the pin 120 and plunger 104 relative to the post 69 connected to the diaphragm 48. This movement of the release pilot valve 83 will therefore be relative to and out of contact with the seat member 85 whereupon fluid under pressure will be vented from chamber 74 within the cylinder 70 at a rate exceeding the rate of supply through the port 75. When the pressure of fluid in chamber 74 is thus sufficiently reduced the pressure of fluid in chamber 63 acting on the opposite side of the release valve 71 will unseat said valve from the end of sleeve 59 against the opposing force of spring 73 whereupon fluid under pressure will be released from chamber 63 and thereby from the reverse bounce chambers in the free piston machine (not shown) to the interior of sleeve 59 and thence through port 72, chamber 71 and passage 67 to atmosphere.

As air is thus released from the reverse bounce chambers in the free piston machine the mean reverse bounce chamber pressure effective in diaphragm chamber 51 will correspondingly reduce

which will permit spring 68 to deflect the diaphragm 48 in the direction of chamber 51. Now assuming that movement of the operator's control handle 137 and thereby of the release pilot valve 83 has ceased, this deflection of diaphragm 48 and of the seat member 85 will be relative to the release pilot valve 83 and finally said seat member will contact said pilot valve in a position of the diaphragm 48 corresponding to that of the operator's control lever 137. When the release pilot valve 83 is thus seated the flow of fluid under pressure from chamber 63 through port 75 into chamber 74 of the cylinder 70 will increase the pressure in said chamber to a degree to permit spring 73 to seat the release valve 71 against the end of sleeve 59 for preventing further release of air from the reverse bounce chambers. The amount of air in the reverse bounce chambers will thus reduce to a degree corresponding to the new position of the operator's control lever 137.

If the lever 137 is pulled still closer to the reader the amount of fluid under pressure present in chamber 63 and the reverse bounce chambers of the free piston machine will reduce further until the substantial mean of the pressure in said chambers acting in chamber 51 is reduced sufficiently for the release pilot valve 83 to again seat for limiting such reduction in accordance with the position of lever 137.

If the lever 137 is returned to the position in which it is shown in the drawing, a complete release of fluid under pressure from chambers 63 and 51 will occur since the diaphragm follower 54 will engage the casing partition 60 with the release pilot valve 83 still open.

It will now be seen that by suitable adjustment of lever 137 any desired amount of fluid may be provided in chamber 63 and thereby in the reverse bounce chambers of a free piston machine wherein during operation of said machine the pressure of such fluid will vary between maximum and minimum values during each stroke of the machine, the substantially constant mean of such varying pressures acting in chamber 51 to limit said amount of fluid in accordance with the position of lever 137. By moving the lever 137 away from the reader the amount of fluid pressure in chamber 63 will be increased according to the extent of such movement, while movement of said lever toward the reader will correspondingly reduce the amount of fluid under pressure present in chamber 63.

Having now described my invention, what I claim as new and desire to secure by Letters Patent, is:

1. A fluid pressure control valve device comprising a casing, a fluid pressure controlling assemblage in said casing comprising a movable abutment subject on one side to pressure of fluid in a pressure control chamber, a regulating spring opposing pressure of fluid in said chamber on said abutment, said assemblage further comprising a sleeve carried by said abutment and projecting into another chamber, a valve in said other chamber cooperative with the end of said sleeve to control a fluid flow communication to said other chamber, a piston of the same area

as the end of said sleeve associated with said abutment at the opposite side thereof, said casing cooperating with said piston to form a balancing chamber at the outer face thereof, and means opening said balancing chamber to said other chamber.

2. A fluid pressure control valve device comprising a casing, a fluid pressure controlling assemblage in said casing comprising a movable abutment subject on one side to pressure of fluid in a pressure control chamber, a regulating spring opposing pressure of fluid in said chamber on said abutment, a sleeve carried by said abutment and projecting into another chamber, a cylinder disposed in said other chamber and carried by said abutment, a valve slidably mounted in said cylinder and arranged to cooperate with the end of said sleeve for controlling a fluid flow communication to said other chamber, a chamber in said cylinder at one side of said valve, a restricted port connecting the last named chamber to said other chamber, a valve carried by said movable abutment controlling a fluid pressure release communication from the last named chamber, and means for opening and closing said valve.

3. A fluid pressure control valve device comprising a casing, a fluid pressure controlling assemblage in said casing comprising a movable abutment subject on one side to pressure of fluid in a pressure control chamber, a regulating spring opposing pressure of fluid in said chamber on said abutment, a sleeve carried by said abutment and projecting into a second chamber, a hollow post-like element carried by said abutment and projecting centrally through said sleeve into said other chamber, a cylinder carried by said post in said other chamber and having one end opening in the direction of the open end of said sleeve, a valve slidably mounted on said post and in said cylinder for seating cooperation with the end of said sleeve, said valve cooperating with the opposite end of said cylinder which is closed to form another control chamber, a restricted port connecting said second chamber to said other control chamber, a hollow member slidably mounted in and extending through said post, means opening said other control chamber to the interior of said hollow member, a pilot valve chamber in said abutment means, means opening said pilot valve chamber to the interior of said hollow member, a pilot valve in said pilot valve chamber cooperating with said abutment means to control a fluid release communication from said other control chamber, and means controlled by movement of said hollow member relative to said post to control opening and closing of said pilot valve.

ARTHUR J. BENT.
